T. C. MORRIS,
FEEDING ROLLER FOR LATH MILLS,
APPLICATION FILED NOV. 23, 1917.

1,278,978.

Patented Sept. 17, 1918.

UNITED STATES PATENT OFFICE.

THOMAS C. MORRIS, OF ATLANTA, GEORGIA, ASSIGNOR TO PETER VREDENBURGH, JR.,
OF VREDENBURGH, ALABAMA.

FEEDING-ROLLER FOR LATH-MILLS.

1,278,978.

Specification of Letters Patent. Patented Sept. 17, 1918.

Application filed November 23, 1917. Serial No. 203,584.

To all whom it may concern:

Be it known that I, THOMAS C. MORRIS, a citizen of the United States, residing at the city of Atlanta, county of Fulton, and State 5 of Georgia, have invented a certain new and useful Improvement in Feeding-Rollers for Lath-Mills, of which the following is a full, clear, and exact description, such as will enable others skilled in the art to which 10 it appertains to make and use the same, reference being had to the accompanying drawings, forming part of this specification.

This invention relates to lumber manufacture, and pertains specifically to certain 15 improvements in a feeding roller for lath mills, of the general type illustrated in the patent to Thomas A. Coleman, No. 1,233,985, granted July 17, 1907.

The purposes of the present invention are 20 to improve generally upon the rollers of the Coleman type designed for use in lath mills to the end of increasing their strength, compactness, accuracy, and security with which the adjustable work-engaging elements are 25 retained in the carrier or drum.

As is well known, in the operation of lath mills, a piece of material is fed by feed rollers against a plurality of saws which rip it into a number of thin strips to form 30 laths. The rollers are subjected to great stress from the operation of the saws upon the material, which have the tendency to kick the material back through the rollers, with probability of injury to the workman, 35 feeding the machine. Accordingly, the work-engaging elements of the rollers are subjected to high pressure as well as vibration, which renders it highly important that they be securely held and supported through- 40 out their length, and that the various adjustable parts of the roller be securely interlocked and held in operative arrangement. Furthermore, due to the disposal of such rollers in the machine, it is desirable that 45 there be no projection or overhang of the end of the shaft beyond the face of the roller. It is the purpose of my invention to meet all of these various requirements, and other objects will be obvious or pointed out 50 hereinafter.

In the accompanying drawings, I have

shown an embodiment of my invention in which—

Figure 1 represents a longitudinal section through one of my improved feed rollers; 55

Fig. 2 a front elevation; and

Fig. 3 a side elevation of one of the engaging elements or tooth bars.

As is well known in the art, the Coleman feed roller of the type described in the patent aforementioned, is characterized by the employment of individually removable work-engaging elements or tooth bars which are suitably held in a drum for coöperation with the work, and which, by manipulation of various adjustable parts of the device, may be loosened so as to permit their removal and replacement when injured. It is this feature upon which my present improvement is predicated.

In the form shown, let the reference character 1 designate the customary shaft upon which the roller is carried and through which it is driven. At a point apart from the extremity of this shaft is keyed a sleeve 2 shaped to provide an annular shoulder 4 and bearing portion 5. The extremity of the shaft is screw-threaded to receive an adjustable sleeve 6 shaped to form an annular clamping shoulder portion 7 disposed counter-facing the shoulder portion 4, and a bearing portion 8 of diameter equal to the bearing portion 5. Rotatably mounted on the bearing portion 5 and shaped to abut the clamping shoulder 4 is a clamping collar 9, 80 and similarly disposed with reference to the bearing portion 8 and the clamping shoulder 7 is a second clamping collar 10.

Mounted on the bearing portions 5 and 8 intermediate said clamping collars is a drum 90 or carrier 11. About its periphery the drum member 11 is provided with longitudinally extending slots 12 disposed at intervals, said slots being of proper depth to receive engaging elements in the form of flat metal bars 95 14 to support them with their work-engaging portions extending beyond the periphery of the drum. The length of these bars is such as to extend beyond the faces of the drum, and adjacent their extremities they 100 are formed, at their inner margins, with reentrant portions 14^a, leaving projecting

portions 14^b extending beyond the reentrant portions for a portion of the width of the bar. Both the reentrant portions 14^a and the projecting portions 14^b extend beyond the 5 faces of the drum member, and the clamping collars 9 and 10 are suitably formed to accommodate and engage them. The collars 9 and 10 are formed with annular undercut portions or grooves 15 shaped to accommodate 10 the reentrant portions 14^a, while the peripheries of said clamping collars are formed with longitudinal slots 16 disposed to register with slots 12, for the accommodation 15 of the extending portions 14^b. The end faces of the drum member 11 are dished or undercut for the accommodation of thick portions 17 of the clamping collars.

The assembly of the device is obvious from the illustrations. The engaging elements 14 20 are placed in the slots 12, the extending portions 14^b being seated in the slots 16 of the clamping collar 9, and the reentrant portions 14^a being engaged in the undercut portion 15 of said collar. The clamping collar 10 is 25 then placed in engagement with the other extremities of the tooth bars in similar fashion, and the adjustable sleeve 6 is then turned up against the shoulder of the clamping collar 10. The pressure thereby exerted upon 30 the clamping collar 10 is transmitted to the engaging elements which, by virtue of the engagement of the reentrant portions 14^a in the undercut portions 15 of the clamping collars 9 and 10, are drawn into their seats 35 and securely clamped therein. Throughout their length, intermediate the faces of the roller, the engaging elements are firmly supported and held, by virtue of their engagement, throughout most of their length, in 40 the slots 12, and at their extremities, in the slots 16. When it is desired to remove any of the engaging elements, the adjustable sleeve 6 is backed off and the clamping collar 10 slid away from the drum 10 to free 45 the extremities of the bars.

By virtue of this construction, not only are the engaging elements firmly secured and supported throughout their lengths, but the necessity for any overhang or projection 50 of the shaft beyond the face of the roller is obviated, and the peripheral face of the roller is traversed throughout its entire extent by the engaging elements, so that there is no area at the extremity of the roller in 55 which a narrow strip would be permitted to ride. Consequently, this construction effectively prevents the kicking back of pieces of work which it is feeding, and thereby forms an effective safeguard for the operator 60 of the machine. The construction, moreover, provides an exceptionally strong device, and one in which it is impossible for the various parts to get out of alinement so as to bind the tooth bars or destroy the

accuracy of the feed. The support of the 65 drum 11 upon the bearing portions 5 and 8 holds all of these parts in proper alinement and effectively prevents the transmittal of any bending movements to the shaft between the clamping elements 2 and 6, thereby preserving the alinement of the latter. In addition to its strength and compactness, the device admits of the desired adjustments 70 with the greatest facility.

While I believe the form which I have 75 illustrated herein and described above to be the best form of the invention, I am aware that it may be embodied in other forms, and that it may be modified in various particulars. It is my purpose and intention that 80 the appended claims comprehend all such other forms and modifications.

What I claim is:

1. A feeding roller comprising a shaft, a pair of sleeves mounted thereupon, one of 85 said sleeves being fixed to the shaft and the other sleeve being adjustable toward and away from the fixed sleeve, a clamping collar positioned upon each sleeve and having a shouldered bearing thereupon, a drum 90 mounted on the sleeves between the clamping collars, said drum and clamping collars having registering longitudinal slots disposed at intervals about their peripheries, and work engaging elements removably 95 seated in said slots and extending continuously from the outer face of one clamping collar to the outer face of the other collar.

2. A feeding roller comprising a shaft, a pair of sleeves mounted thereupon, one of 100 said sleeves being fixed to the shaft and the other sleeve being adjustable toward and away from the fixed sleeve, a clamping collar positioned upon each sleeve and having a shouldered bearing thereupon, a drum 105 mounted on the sleeves between the clamping collars, said drum and clamping collars having registering longitudinal slots disposed at intervals about their peripheries, work 110 engaging elements removably seated in said slots and extending continuously from the outer face of one clamping collar to the outer face of the other collar, and the ends of said work engaging elements and the inner faces of the clamping collars having inner 115 engaging shoulders.

3. A feeding roller comprising a shaft, a pair of sleeves mounted thereupon, one of 120 said sleeves being fixed to the shaft and the other sleeve being adjustable toward and away from the fixed sleeve, a clamping collar positioned upon each sleeve and having a shouldered bearing thereupon, a drum 125 mounted on the sleeves between the clamping collars, said drum and clamping collars having registering longitudinal slots disposed at intervals about their peripheries, and work engaging elements removably seat-

ed in said slots and extending continuously from the outer face of one clamping collar to the outer face of the other collar, the end portions of said work engaging elements being provided with angular shoulders and the inner faces of the clamping collars being provided with grooves adapted to receive said angular shoulders.

4. A feeding roller comprising a shaft 10 having a threaded portion, a sleeve rigidly fixed on the shaft adjacent to said threaded portion, a sleeve screw-seated on the threaded portion of the shaft, both sleeves being provided with annular shoulders, a clamping collar mounted on each sleeve and having a shoulder adapted to bear against the shoulder on the sleeve, a drum mounted on

the sleeves between the clamping collars, the periphery of which drum is provided with a series of longitudinally disposed slots, the peripheries of the clamping collars being provided with longitudinally disposed slots which are adapted to coincide with the slots in the drum, the inner faces of the clamping collars adjacent to their peripheries being provided with shoulders, and work engaging elements removably seated in the slots in the drum and clamping collars, the end portions of which work engaging elements are provided with shoulders which are adapted to engage in the grooves in the collars.

In testimony whereof I hereunto affix my signature, this fifth day of November, 1917.

T. C. MORRIS.
